UNITED STATES PATENT OFFICE.

CHARLES W. KIRSCH, OF STURGIS, MICHIGAN, ASSIGNOR TO KIRSCH MANUFACTURING CO., OF STURGIS, MICHIGAN, A CORPORATION OF MICHIGAN.

CURTAIN-ROD LOCK.

1,142,438.

Specification of Letters Patent.

Patented June 8, 1915.

Application filed September 23, 1912. Serial No. 721,834.

To all whom it may concern:

Be it known that I, CHARLES W. KIRSCH, citizen of the United States, residing at Sturgis, in the county of St. Joseph and 5 State of Michigan, have invented certain new and useful Improvements in Curtain-Rod Locks; and I do hereby declare the following to be a full, clear, and exact description of the invention, such as will enable 10 others skilled in the art to which it appertains to make and use the same.

This invention relates to improvements in extensible or adjustable curtain rods and has for its object to provide a telescopically 15 adjustable curtain rod and means for locking the relatively movable parts against such relative movement after the rod has been adjusted to the desired length.

The invention resides in the features of 20 construction and combinations of parts hereinafter fully described and particularly claimed.

In the accompanying drawings illustrating the invention: Figure —1— is a fragmentary view in elevation of the inner face of a curtain rod composed of two telescopically interfitting parts and showing the locking means engaged therein in position to prevent relative telescopic movement of said 25 parts. Fig. —2— is a detail vertical transverse section of the same on the line 2—2 of Fig. —1—. Fig. —3— is a detail perspective view of a wrench employed for operating the locking device. Fig. —4— is a detail perspective view of one of the locking devices.

My invention relates particularly to that type of curtain rod made of sheet metal and comprises flat strips A and C each having 40 U-shaped opposed flanges B and D respectively, and which are made in such relative widths and dimensions as to enable the part A to fit telescopically within the similar part C. The said interfitting parts of the two 45 channel-shaped members A and C may be of any desired number and relative sizes to build up curtain rods or the like of any desired lengths.

Telescopically adjustable curtain rods are 50 very convenient and easily adjusted in length but when so adjusted they are also easily thrown out of adjustment by accident or careless handling and it is sometimes a matter of considerable difficulty, especially 55 when the curtains are mounted on the rod,

to re-adjust the same preparatory to hanging the rod on its supports.

The particular object of the present invention is to provide simple and efficient means for locking the two or more parts of a curtain rod of the type described against relative movement after the same has been once adjusted to the proper length. The said locking means consists of a disk or cam E of sheet metal which is slightly elliptical, that 60 is to say, it has one diameter greater than the greatest inner width of the rod A between its flanges B and another diameter less than said dimension. The said disk E may obviously be easily inserted between the 65 flanges B of the rod A and into that portion of said rod which lies within the rod C and between the flanges D of the latter. The said disk E is provided in its middle portion with an elongated slot F in which the 70 end of the arm G of the wrench H is adapted to engage and by means of which said disk E may be turned through an arc of ninety degrees more or less when disposed within the rod A thereby causing the flanges 75 B thereof to be expanded and thus to frictionally engage the flanges D of the rod C to prevent relative telescopic movement of said rods A and C except by the exercise of great force. While one of said disks E is usually 80 sufficient to effectually prevent relative telescopic movement of two rods A and C several of said disks may be inserted as indicated in Fig. —1—.

It will be obvious that the slots between 85 the opposed flanges of both of the members, A and C, will readily permit access to the disk or cam E, so that the latter may be partially rotated to expand an adjacent portion of the member A against the part of the 90 member C, which otherwise slidably overlaps the said portion of the member A, and that when the said cam is released from its expanding position, the resiliency of the member A will return the said portion of 95 the latter to its former loose fitting of the adjacent part of the member C. It will also be evident that by using a locking element E, loosely slidable within the smaller of the rod members, this element may readily be so 100 positioned as to be most effective in its expanding action.

I claim as my invention:

1. A curtain rod including a pair of channel-shaped members each equipped with op- 110

posed overhanging flanges bordering a slot longitudinal of the member carrying said flanges, the first of said members made of resilient material and presenting a portion 5 slidably disposed within a part of the second member; and means housed by the said portion of the first member and operable through the slot of both members for expanding the said portion of the first member 10 into engagement with the adjacent part of the second member, the resiliency of the portion thus expanded returning the said portion of the first member to its normal size upon a release of the said expanding 15 means.

2. A curtain rod including a pair of channel-shaped members each equipped with opposed overhanging flanges bordering a slot longitudinal of the member carrying said

flanges, the first of said members made of 20 resilient material and presenting a portion disposed with a part of the second member, the said portion being normally contracted by its own resiliency to loosely fit the adjacent part of the second member; a cam disposed within the said portion of one of said members, and means operable through both said slots for rotating said cam to cause the latter to expand the said portion of the first member into interlocking engagement with 25 the adjacent part of the second member.

In testimony whereof I have signed my name in presence of two subscribing witnesses.

CHARLES W. KIRSCH.
